UNITED STATES PATENT OFFICE.

CHARLES H. DAY, OF ST. PAUL, MINNESOTA.

ROAD-CROSSING SIGNAL.

Application filed November 28, 1923. Serial No. 677,497.

To all whom it may concern:

Be it known that I, CHARLES H. DAY, a citizen of the United States, residing at St. Paul, in the county of Ramsey and State 5 of Minnesota, have invented certain new and useful Improvements in Road-Crossing Signals, of which the following is a specification.

This invention relates to safety signals 10 used at crossings of railroads and country roads or streets and the object is to provide an effective device of said kind whereby vehicles and pedestrians who are about to cross a railway track may duly and timely 15 be signaled the approach, position and passing of trains.

In the accompanying drawing:

Fig. 1 is a plan view of a portion of a railway track and its bed crossed by a drive road and provided with my signal device 20 and the electric wiring shown mainly in diagram.

Fig. 2 is a side elevation of Fig. 1.

Fig. 3 is an enlarged portion of Fig. 2 25 showing one of the switch boxes in section.

Fig. 4 is a modification of Fig. 3.

Referring to the drawing by reference numerals, 5 designates a roadway crossed by a railroad of which only a single track is 30 shown and comprises a pair of rails 7 shown as secured on ties 8.

Near one side of the roadway 5 and suitably spaced from the track I put up a post 9 and a similar post 9^a near the other side 35 of the road 5 and the track. Said posts and their equipments being alike a description of one will answer for both.

P P P in Fig. 1 indicate track portions each hundreds of feet long, broken away for 40 want of space on the drawing.

Each post is firmly secured in the ground or to an extra long tie as 8^a. Secured on each post is a box 10 containing a suitable electric battery 11, unless some live wire is 45 available instead of a local battery.

Upon the top of the post I mount a box 12 which is oblong in the direction of the track. The sides and end of the box are transparent and within the box are mounted 50 a row of electric lamps A, B, C, D, E and F of which the latter is nearest to the roadway 5 and is extra large and gives a red light. All the lamps in the same box are connected to a wire 13—14 extending to the negative pole of the battery. Each lamp also 55 has a wire A², B², C², D², E² or F² each

extending to a switch box 15 mounted on a special block 16 secured in the road bed about half way between a pair of ties the distance between the switch boxes may be 60 several hundred feet.

Each switch box, as best shown in Fig. 3, has a push button 17 with insulation 18 for the rail to press down upon as often as the rail is sprung downward by a car wheel 65 as will presently be further described.

The first switch is placed about four hundred feet away from the street or driveway 5, and the other switches may be placed a similar distance from each other. Each 70 switch has a wire 19 leading to a comparatively long wire 20 extending to the positive pole of the battery (or to either pole not occupied by the wire 14).

Each switch comprises a metal box 21 secured by nails or like means 22 upon its block 15. In said box or inclosure is pivoted at 23 a lever 24 having a short arm 25 rigidly fixed to the push button 17 as in Fig. 3, or pivoted as at 26 in Fig. 4 and a longer and resilient weighted arm 27 arranged to swing upward and yieldingly form contact a contact port 28 from which wire 19—20 may extend to the battery while one of the wires A², B², C² etc. connects lever 85 27 with one of its lamps.

The arrangement just described is in Fig. 4 so modified that the lever 24 is fulcrumed in a bracket 29 secured by insulation 30, and post 28 stands vertically. The arrows in 90 Figs. 3 and 4 may point either way according to how the battery is connected in the circuit. The main advantage in Fig. 4 is that the press button moves more vertically than in Fig. 3.

In the operation of the device, when a train passes over the rails and causes the well known wave motion between the ties the rail above the switch button will be sprung downwardly by each passing wheel 100 and although the vertical vibration may be but slight the long arm 23 of the switch lever increases the motion and closes the switch. In some cases the closing might be too hard but this is provided for by the 105 resiliency of the arm 23.

In this manner a train approaching the roadway 5 will first cause the lamp A to light up and flutter, then lamps B, C, D and E likewise in succession as a warning 110 to travelers on the road 5, to be careful if crossing the track and when the train is as

near as about four hundred feet it will cause the large, red light at F to shine and flutter as a sharp warning that the train is so near that no one should risk crossing the track 5 no matter how carefully until the train has passed the crossing.

If the driver or pedestrian on road 5 can not see the train because of hills or woods 10 he can still see by the lamps in the signal that a train is near and he can also see in which direction it moves, since if it is moving away from the driveway the light nearest thereto will go out and then the next and next light further away, while if the 15 train is approaching the lighted lamps will be increasing in numbers. It will be understood that the signal arrangement at either side of the road 5 signals as to a train approaching road 5 and the arrangement at 20 the other side of road 5 signals the departure of trains away from the road. If the railway has two tracks for trains to run in opposite directions, then each track should have all the electric switches under one of 25 its rails; but the same two posts with lamps, as described, will answer for the double

tracked road. If so desired, audible signal devices may also be operated in connection with the lighting of the lamps, but as audible signals are not broadly new I will not 30 describe or try to claim them.

What I claim is:

A road crossing signal adapted to be operated by a railway train moving in a certain direction, said signal comprising a transparent inclosure near the crossing, a straight row of electric lamps arranged in the inclosure parallel to the track rail, the lamp at the end of the row last to be passed by the train being larger than the other 35 lamps and of a special color, a source of electricity, a series of switches spaced along the road bed and adapted to be operated by a passing train, and circuit wires connecting the switches with the lamps in such a manner that the moving train causes the lighting of the lamps successively in the direction the train is moving.

In testimony whereof I affix my signature:

CHARLES H. DAY.
